UNITED STATES PATENT OFFICE.

STANLEY H. KNIGHT, OF CHICAGO, ILLINOIS.

MEASURING-FAUCET.

1,374,665.

Specification of Letters Patent. Patented Apr. 12, 1921.

Application filed May 14, 1920. Serial No. 381,266.

To all whom it may concern:

Be it known that I, STANLEY H. KNIGHT, a citizen of the United States of America, and a resident of Chicago, in the county of 5 Cook, State of Illinois, have invented certain new and useful Improvements in Measuring-Faucets, of which the following is a specification.

This invention relates to that class of dispensing faucets for soda fountain and like uses, in which a quantity of a sweetening or flavoring fluid is measured off and mixed with carbonated water during the flow of the same from the faucet, and more especially relates to the type of such faucets which constitutes the subject matter of my prior Letters Patent No. 1,323,069, dated November 25, 1919 and No. 1,327,162, dated January 26, 1920.

20 The present improvement has for its object, to provide in connection with the dispensing means of my prior patented construction, a simple and efficient structural formation and association of parts whereby 25 a predetermined and fixed quantity of the sweetening or flavoring fluid is measured off and then discharged into the path of the flow of the carbonated water, all as will hereinafter more fully appear.

30 In the accompanying drawings:—

Figure 1, is a perspective view illustrating the general and preferred arrangement of parts in the present improvement.

Fig. 2, is a central vertical sectional elevation of the faucet structure, showing the controlling valve of the measuring means in a closed condition.

Fig. 3, is a companion section on line 3—3 Fig. 4 showing said valve in an open condition.

Fig. 4, is a horizontal section on line 4—4 Fig. 2.

Like reference numbers indicate like parts in the several views.

45 As represented in the drawings, the preferred formation and association of the parts are substantially the same as in my prior Patent No. 1,323,069 aforesaid, and comprises a construction as follows:—

50 1 designates the outlet neck of a soda fountain provided at its upper and forward end with a controlling faucet 2 by which the flow of carbonated water is manually controlled. The faucet 2 is preferably of the 55 semi-rotary type and provided with an operating handle 3 and with an outlet neck 4 at

its lower end terminating in a discharge nozzle 5 for the carbonated water.

6 designates an elevated supply tank for the syrup or like flavoring fluid used, preferably secured to the outlet neck 1 by means of a clamp bracket 7 or other like connecting means.

8 designates a circular head or disk fixedly connected to the outlet neck 4 of the faucet 65 2 with its perimeter formed for the attachment of the hereinafter described coupling sleeve.

In the present improvement the head 8 is formed from concentric walls 9 and 10 integrally connected by a bottom wall or web 11 to provide a closed annular measuring chamber 12 as shown in Figs. 2 and 4. Such measuring chamber encircles the discharge nozzle 5 with its inner annular wall forming 75 a free passage for the downward discharge of the carbonated water from said nozzle.

13 designates a vent pipe or passage connecting the upper end of the measuring chamber 12 with the supply tank 6, to insure 80 a free flow of syrup or the like from said supply tank into the measuring chamber.

14 designates a valve housing arranged in one side of the measuring chamber 12, with its upper end in connection with a tubular neck 15, which in turn is connected by a supply pipe or passage 16 with the supply tank 6 aforesaid.

17 and 18 designate upper and lower valve seats formed in the valve housing 14 aforesaid. 90

19 designates a lateral opening or passage connecting the space between the valve seats 17, 18 with the measuring chamber 6 aforesaid. 95

20 designates a vertically movable valve head arranged intermediate of the valve seats 17, 18 and adapted for alternate seating contact with said seats in the operation of the appliance. The valve head 20 is preferably of the vertically guided type shown, and provided with a depending operating stem 21 adapted for operative engagement with an annular ledge of the movable hopper or vessel hereinafter described. With the 100 valve head 20 in its lower position shown in Fig. 2, communication is open between the supply tank 6 and measuring chamber 12, with the outlet from said measuring chamber closed by the valve head 20 seated upon 110 the lower valve seat 18. With the valve head 20 in its upper position shown in Fig.

3, the outlet from the measuring chamber 12, through opening 19 and lower valve seat 18 is open, while the inlet from the supply tank 6 is closed by the valve head 20 seated against the upper valve seat 17.

22 designates a movable hopper or vessel, similar in construction and operation to the movable hopper or vessel described in my prior Patent No. 1,323,069 and having an outlet neck 23 at bottom, an outturned flange 24 at top, and an internal annular ledge 25 as shown in Figs. 2 and 3.

26 designates a coupling sleeve screwed upon or otherwise secured to the perimeter of the head or disk 8 aforesaid, and having at its lower end an inturned annular flange 27 adapted to engage beneath the outturned flange 24 of the hopper 22 to hold the same in place and at the same time permit of limited vertical movement of said hopper in relation to the head 8 in a practical operation of the apparatus.

28 designates an operating cross head fixedly secured to the outlet neck 23 of the hopper 22 with its cross arms extending away from the sides of said neck to afford abutments against which the attendant can press the rim of a dispensing goblet or the like, in an attainment of an upward movement of the hopper 22 and a flow of syrup or like flavoring fluid.

Having thus fully described my said invention what I claim as new and desire to secure by Letters Patent, is:—

35 1. In a dispensing faucet, the combination of a main supply controlling faucet, a measuring chamber associated with said faucet, a secondary valve controlling the inlet to and the outlet from said measuring 40 chamber, and a receiving hopper having limited independent movement in relation to said faucet and measuring chamber, said hopper having operative engagement with said secondary valve.

45 2. In a dispensing faucet, the combination of a main supply controlling faucet, a measuring chamber associated with said faucet and having an annular form, a secondary valve controlling the inlet to and 50 the outlet from said measuring chamber, and a receiving hopper having limited independent movement in relation to said faucet and measuring chamber, said hopper having operative engagement with said secondary valve.

3. In a dispensing faucet, the combination of a main supply controlling faucet having a circular head at its outlet end, a measuring chamber associated with said head, a valve housing associated with said measuring chamber, a valve head arranged in said housing and controlling the inlet to and the outlet from said measuring chamber, and means for manually actuating said valve head.

4. In a dispensing faucet, the combination of a main supply controlling faucet having a circular head at its outlet end, a measuring chamber associated with said head, a valve housing associated with said measuring chamber, a valve head arranged in said housing and controlling the inlet to and the outlet from said measuring chamber, a receiving hopper attached in a vertically movable manner to said head and provided with means for operating said valve head, and an operating cross head associated with said hopper.

5. In a dispensing faucet, the combination of a main supply controlling faucet having a circular head at its outlet end, a measuring chamber associated with said head, a valve housing associated with said measuring chamber, a valve head having a depending stem, arranged in said valve housing to control the inlet to and the outlet from said measuring chamber, a receiving hopper attached in a vertically movable manner to said head and provided with means for operating said valve head, and an operating cross head associated with said hopper.

6. In a dispensing faucet, the combination of a main supply controlling faucet having a circular head at its outlet end, a measuring chamber associated with said head and having an annular form, a valve housing associated with said measuring chamber, a valve head having a depending stem, arranged in said valve housing and controlling the inlet to and the outlet from said measuring chamber, a receiving hopper attached in a vertically movable manner to said head and provided with an internal annular ledge for operative engagement with the depending valve stem aforesaid, and an operating cross head associated with said hopper.

Signed at Chicago, Illinois, this 11th day of May, 1920.

STANLEY H. KNIGHT.
